UNITED STATES PATENT OFFICE.

JOSEPH JAUCH, OF LOS ANGELES, CALIFORNIA.

RADIATOR.

1,319,285.

Specification of Letters Patent.

Patented Oct. 21, 1919.

Application filed March 26, 1919. Serial No. 285,366.

To all whom it may concern:

Be it known that I, JOSEPH JAUCH, a citizen of the United States, residing at Los Angeles, in the county of Los Angeles and 5 State of California, have invented new and useful Improvements in Radiators, of which the following is a specification.

My object is to make an improved radiator construction for cooling water as used 10 in connection with internal combustion engines, and my invention consists of the novel features herein shown, described and claimed.

Figure 1 is a fragmentary elevation of 15 a radiator construction, embodying the principles of my invention, as seen looking in the direction indicated by the arrow 1 in Fig. 3.

Fig. 2 is a fragmentary end elevation 20 showing two channel members ready to go together.

Fig. 3 is a fragmentary cross section on the line 3—3 of Fig. 1.

Fig. 4 is a fragmentary cross section on 25 the line 4—4 of Fig. 3.

Fig. 5 is a fragmentary perspective of one plate of the channel member as indicated by the arrow 5 in Fig. 2.

Fig. 6 is a fragmentary perspective of 30 the other plate of the channel member as indicated by the arrow 6 in Fig. 2.

The body of the radiator is made up of a series of channel members 1, 2 and 3 forming 35 vertical water passages 4, 5 and 6, and horizontal air passages 7, 8 and 9. Each channel member comprises a plate 10 and a plate 11. The plate 10 is transversely bent zigzag to form transverse air passages 12 on each side, and the seats 13 on the other side, and 40 the plate 11 is correspondingly bent zigzag to form the seats 14 on one side and transverse air passages 15 on the other side, so that the plates 10 and 11 will nest together, the bend of the plate 10 forming an air passage 12 fitting in the bend of the plate 11 against the seat 14, and the bend of the plate 11 forming the air passage 15 fitting in the bend of the plate 10 against the seat 13. Upon the side edges of the plates the bends 45

50 are regular and fit together, and these side edges are secured together by soldered joints 16 and 17. Between the edges, or soldered joints, 16 and 17 the plates are formed so as not to fit together, but so as 55 to occupy practically parallel planes and

continuous even passages 4, 5 and 6 between each pair of plates, and one pair of plates fits upon the other so as to form practically even transverse air passages 7, 8 and 9 between the pairs of plates. 60

The plate 10 has square bends 18, 19, 20, 21, 22 and so on, and the plate 11 is bent upon its edges to form the square bends 23, 24, 25, 26, 27 and so on. The plates 10 and 11 are assembled, so that the bends 18 and 22 will fit against the bends 23 and 27, the bends 19, 20 and 21 fit in the channel against the bends 24, 25 and 26, and each member 1, 2, 3 and so on, is constructed in the same way. Seats 28 and 29 are 70 formed inside of the edges of the plates 11 in line with the corners between the bends 24 and 25 and 25 and 26, so that the members are assembled with the corners 30 and 31 of the plates 10 fitting in the seats 28 75 and 29. The plates 10 and 11 are substantially alike with the exception that the plate 11 has the seats 28 and 29. 80

Intermediate of the edges of the plate 10 the plate has bulges 32 between the seats 13, and the plate 11 has bulges 33 between the seats 14. Intermediate of the edges the plate 10 is bent substantially V-shape to form the transverse passage 12 as indicated by the lines 34 and 35, and in a like 85 manner the plate 11 is bent V-shape in the channel 15 as indicated by the lines 36 and 37. The result is that when the members 1, 2, 3 and so on, are assembled the vertical water passages 4, 5 and 6 are formed 90 between the plates of the members, and the air passages 7, 8, 9 and so on, are formed between the members. 95

Thus I have produced a radiator construction forming practically even vertical water 95 passages and practically even transverse air passages, and at the same time producing a strong and durable construction which is simple and easily made, and which presents the largest possible area of water to the 100 largest possible area of air.

Various changes may be made without departing from the spirit of my invention as claimed.

I claim:

1. In a radiator, two plates bent at their edges to form right angled equally spaced zigzag lines and fitting together at their edges and soldered together, said plates being bent and pressed intermediate of their 110

edges to fit together to form a zigzag water passage on the lines of alternately inverted V's.

2. In a radiator, two members; each member comprising two plates bent at their edges to form right angled equally spaced zigzag lines and fitting together at their edges and soldered together, said plates be-

ing bent and pressed intermediate of their edges to fit together to form a zigzag water 10 passage on the lines of alternately inverted V's, and said members fitting together to form a transverse air passage.

In testimony whereof I have signed my name to this specification.

J. JAUCH.
